(57) **CLAIM**

The ornamental design for a storage locker, as shown and described.

DESCRIPTION

FIG. 1 is a perspective view of an embodiment of a storage locker;

FIG. 2 is a right side view of the storage locker illustrated in FIG. 1;

FIG. 3 is a left side view of the storage locker illustrated in FIG. 1 with some of the unclaimed subject matter removed; FIG. 4 is a front view of the storage locker illustrated in FIG. 1;

FIG. 5 is a rear view of the storage locker illustrated in FIG. 1;

FIG. 6 is a top view of the storage locker illustrated in FIG. 1; and,

FIG. 7 is a bottom view of the storage locker illustrated in FIG. 1.

The broken lines are included for purposes of illustration and form no part of the claimed design.

1 Claim, 7 Drawing Sheets
